ATTORNEY

UNITED STATES PATENT OFFICE.

WILLIAM G. HILL, OF BROOKLYN, NEW YORK.

DUSTLESS CHALK-TRough.

Specification of Letters Patent.

Patented Feb. 24, 1920.

1,331,767.

Application filed May 27, 1919. Serial No. 300,111.

To all whom it may concern:

Be it known that I, WILLIAM G. HILL, a citizen of the United States, residing at New York, borough of Brooklyn, in the county of 5 Kings and State of New York, have invented a new and useful Dustless Chalk-Trough, of which the following is a specification.

This invention relates to troughs for holding chalk; and has for its objects: 1, to provide a trough so mounted in relation to a "black board" that all the chalk dust coming from the erasures of figures, writing, and the like, on the board, as well as all chalk dust coming from the chalk crayons, on laying the same down, and picking them up, is bound to enter the trough, and be held in an easily-removable manner; 2, to provide a chalk trough that will be securely held in position when desired, and which can be easily and readily removed when desired to clean it; 3, to provide a chalk trough which can be readily emptied when desired without breaking up, or scattering the dust; and, 4, 20 to provide a chalk trough which is cheap to manufacture, and efficient in use.

The invention is illustrated in the accompanying drawing, in which—

Figure 1, is a sectional view of my improved dustless chalk trough applied to a "slate blackboard"—the blackboard and what is shown of the frame being also in section; and,

Fig. 2, is a perspective view of the under side and inner edge of my invention.

It may be stated that while the invention is shown as applied to a slate blackboard; and is exceedingly desirable, and easily applied to a frame for that kind of a blackboard; I do not confine myself to the use of the invention solely in connection with a slate blackboard.

In the drawing, like numerals of reference refer to the same parts in each of the views.

In the practice of my invention I provide a dustless chalk box 3, having a wire mesh top 4, on which the pieces of chalk crayons may be placed when not in use; and the wire mesh or screen 4 is held in place by the two side strips 5 and end strips 6 so that the box, or trough is completely covered with the screen 4, which is spaced a sufficient distance above the bottom of the trough that the chalk dust from the pieces of crayon, or from the blackboard will have ample room to lie in

the box, or trough below the screen, as will be understood.

In the drawing, as previously stated, the invention is shown as applied to a slate blackboard, a portion 7 of which is shown. 60 This slate is spaced from the wall with the strip 8, rests on the strip 9, and is held in place with the molding strip 10.

In mounting my improved chalk trough I prefer to provide another strip 11 directly 65 beneath the strip 9, and face this with a molding strip 12, having a flat face 13; and the strips 11 and 12 may rest on a molding strip 14, as will be understood.

In practice I so proportion the parts that 70 my improved chalk trough will slip under the molding strip 10, holding the slate blackboard in place, and rest on the strips 11 and 12. This trough is held in an easily-removable manner so that when it is desired to remove the trough dust, or the chalk dust that has fallen into the trough, the trough itself 75 may be easily displaced and taken where the dust may be dumped. As shown, I provide for the ready removal of the trough by providing the latch 15, which co-operates with the catch 16, which may be located anywhere on the bottom of the trough 3 that is most desirable. The flat face 13, of the molding strip 12 provides for the easy mounting of 80 85 the catch 15, as will be understood.

The box, or chalk trough 3, is provided adjacent to one end with an opening 17, which lies wholly below the netting 4, so that the chalk dust can be dumped through 90 this opening without having to engage the screen.

In operation, the chalk trough is so mounted, as described, underneath the molding strip at the bottom of the blackboard 95 that all chalk dust coming from the blackboard must enter the trough; and the trough is of sufficient width that there is little possibility of the dust flying outwardly beyond the same. When desired to clean the trough, 100 the same can be easily removed by unfastening the catch at the bottom of the trough; the trough can then be taken where it is desired to dump the same and by thumping the end of the trough against some object 105 while holding the trough in an inclined position all the chalk dust can be brought down to the end of the trough where the opening 17 is located, and can then be dumped out through the opening 17 without 110

the necessity of passing the dust through the screen 4 and breaking up and scattering the same. After the dust has been discharged from the trough, the trough can 5 again be placed back in position, as will be readily understood.

It will thus be seen that I have provided a dustless chalk trough so constructed and mounted that there is no possibility of any 10 chalk dust engaging the outer side of the trough; and which can be cleaned in a simple and efficient manner without scattering the chalk dust. The mounting of the chalk trough between the molding strips, as 15 shown provides for the firm holding of the same, while the latch and catch provides for the firm holding of the trough against displacement while in use.

I claim:

20 1. A dustless chalk trough comprising a box, a screen cover therefor, strips to hold said screen in place, and said trough having an opening in one side thereof adjacent to the end beneath said screen cover, and means 25 to close said opening with the wall of the building when in use for the purpose set forth.

2. The combination with a slate black-board held in place with strips of molding 30 whereby an outer strip of molding is provided at the bottom of the blackboard, of a dustless chalk trough having a screen chalk holder and an opening in the side of the box adjacent to one end beneath said screen, 35 the side having the opening being adapted to fit under the inner, under side of said outer strip of molding whereby the said molding strip partially overhangs the interior of said trough.

40 3. The combination with a slate black-board held in place with strips of molding whereby an outer strip of molding is provided at the bottom of the blackboard, of a dustless chalk trough having a screen chalk 45 holder and an opening in the side of the box adjacent to one end and beneath said screen, the side having the opening being adapted to fit under the inner, under side of said outer strip of molding whereby the 50 said molding strip partially overhangs the interior of said trough, and means to detachably hold said trough in place.

4. A dustless chalk trough comprising a box and a wire screen mounted therein intermediate of the top and bottom, said box having an opening in one side thereof beneath said screen, and detachable means to hold said trough beneath a blackboard in a manner whereby all dust falling from said 60 blackboard must enter said trough.

5. A chalk trough having a screen spaced from the bottom, and a discharge opening in one side thereof between the screen and the bottom of the trough and means to close said opening with the wall of the 65 building when in use.

6. The combination with a blackboard of a chalk trough having a screen spaced from the bottom, and a discharge port adjacent to one end thereof between said screen and 70 the bottom of the trough, means to direct all the chalk dust falling from said blackboard into said trough, and means to close said discharge port.

7. A chalk trough in combination with a 75 blackboard, said trough having a screen spaced from the bottom thereof, and a discharge port in one side thereof between the screen and the bottom of the trough, and means to hold the side of said trough with 80 the discharge port against the wall whereby the said port is closed while the trough is in use.

8. The combination with a slate black-board held in place with strips of wood and 85 moldings, of a chalk trough having a screen spaced from the bottom, and a discharge port in one side thereof between the screen and the bottom of the trough, means to hold said trough against the molding at the 90 bottom of the blackboard in a manner whereby the molding will partially overlie said screen, and the side of the trough having the discharge port against the wood supporting said blackboard, and means to 95 easily remove said trough from said position.

9. In combination, a slate blackboard held in place at the bottom with an inner, and a supporting strip of wood, and an 100 outer strip of molding, a chalk trough comprising a box having an opening in the side thereof adjacent to one end, a screen cover, and strips on the top edges of the box holding said cover in place, said trough being 105 mounted beneath the strip of molding at the bottom of the blackboard with a portion of the screen cover overhung with said molding, said trough being supported on the under side with a molding strip and a 110 wood backing, a catch operating in conjunction with the molding on which the trough partially rests and the bottom of the trough whereby the trough is securely held in place with the opening in the side thereof 115 against the strip of wood supporting said slate blackboard.

Dated this 8th day of May, 1919.

WILLIAM G. HILL.
